US0D1038180S

(12) **United States Design Patent** (10) Patent No.: **US D1,038,180 S**
Buchet et al. (45) Date of Patent: ** Aug. 6, 2024

(54) **TEXTILE MACHINE**

(71) Applicant: **STAUBLI LYON**, Chassieu (FR)

(72) Inventors: **Baptiste Buchet**, Meyzieu (FR); **Pascal Guenard**, Chaponnay (FR)

(73) Assignee: **STAUBLI LYON**, Chassieu (FR)

(**) Term: **15 Years**

(21) Appl. No.: **35/519,103**

(22) Filed: **Nov. 10, 2023**

(80) **Hague Agreement Data**

Int. Filing Date: **Nov. 10, 2023**

Int. Reg. No.: **DM/233122**

Int. Reg. Date: **Nov. 10, 2023**

Int. Reg. Pub. Date: **Nov. 24, 2023**

(30) **Foreign Application Priority Data**

May 17, 2023 (WO) WIPO133032
